ABSTRACT OF THE DISCLOSURE

In electro-fluid-dynamic power conversion apparatus, limits of pressure and density of the ion transport gas are reached where the desirable corona discharge for generating ions breaks down into a spark or plasma type discharge. To avoid this condition, the gas duct is constructed to include an electrically conducting expansion nozzle, charged to a high electrical potential and also serving as an attractor electrode. A corona generating electrode is positioned adjacent the throat of the expansion nozzle and is heated to a high temperature. In the boundary layer in the immediate vicinity of the corona electrode, due to the high temperature, there exists a zone of relatively low gas density and correspondingly low breakdown field strength. An abundant stream of unipolar ions can then be pulled into the gas stream from the heated corona electrode by the attractor electrode potential and be swept downstream in the jet discharge of the expansion nozzle.

The invention described herein may be manufactured and used by or for the United States Government for governmental purposes without payment to us of any royalty thereon.

The invention relates to improvements in electro-fluid-dynamic power conversion apparatus of the type disclosed in United States Patent 3,225,225 issued Dec. 21, 1965. In the patented power generating system, ions are seeded into a high velocity gas system and the ions are accelerated by the gas molecules at the expense of the energy of the gas stream. Doing work on the ions corresponds to an increase in their electrical potential with respect to ground and the charged particles give up their electrical charges to a collector electrode assembly. The collector electrode assembly at a high potential is connected to an external load circuit. In order to increase the electrical power generating capacity of the patented system, it is essential to generate large quantities of unipolar ions or charged particles in very dense high velocity gas flows. It is well known that unipolar ions can be generated by a corona discharge. However, when the transport gas density is greatly increased with respect to atmospheric conditions, it reaches a level at which the corona discharge phenomena discontinues rather abruptly in spite of an extremely high electrical potential between the corona and attractor electrodes. The desirable corona discharge breaks down into a spark or plasma arc type discharge when the limiting conditions are reached, which interrupts the ion generation.

It is the object of the present invention to remove the upper density limitation heretofore present in electric power generating of the type described. In accordance with the invention, a very effective corona discharge can be obtained even under extremely high gas density conditions where normally only spark discharge can be obtained. How this desirable objective is obtained is as follows. An expanding gas flows through a nozzle which is made of an electrically conducting material and connected

to a source of high electric potential. The expansion nozzle serves also as an attractor electrode. The corona generating electrode is positioned within the expansion nozzle and is constructed so that its external surface, or at least the tip is heated to a high temperature, for example, electrically. Even under extremely high gas pressure conditions, by this arrangement an abundant supply of unipolar ions or other charged particles will be released from the corona electrode by the combined effects of (a) extremely high electrostatic field strength concentration at the surface of the corona electrode and (b) high corona electrode temperature with associated low local gas density with correspondingly low breakdown field strength in the immediate vicinity of the heated electrode surface.

Other more specific features of the invention will become apparent by reference to the detailed description hereinafter given when taken in conjunction with the appended drawings, in which;

FIG. 1 illustrates a longitudinal sectional view of an ion generating equipment in accordance with the invention; and

FIG. 2 is a view similar to FIG. 1 illustrating a modified corona electrode in the shape of a ring.

With reference now to FIG. 1, the reference numeral 25 generally indicates a duct adapted to conduct a gas at high pressure, for example, of the order of 100 atmospheres. The duct has a tubular metal entrance portion 2 adapted to be connected to a source of gas under high pressure (not shown). The gas may, for example, be high pressure steam, air, carbon dioxide, metal vapors and the like. The duct portion 2 connects to a hollow electrically insulating section 3 which may, for example, be made of a ceramic liner portion covered by resin impregnated fiberglass to withstand high pressure. The duct section 30 contains a cylindrical insulating support 4 adapted to house electrical conductors 6 which are connected by high temperature brazing or the like to a conical metal tip 8 made from a high resistance metal alloy so as to be heated to a high temperature when an electric current is passed therethrough. The conductors 6 are adapted to be connected in series with the tip 8 to an external source of electric current, for example, the battery 10, by conductors 11 and 12 and the heater circuit being electrically grounded as indicated at 14.

The insulating duct section 3 connects on its downstream side to a nozzle section 15 made of metal or other electrically conducting material. The nozzle section 15 is internally contoured into a convergent entrance section 16, a throat 17 and a divergent diffuser section 18. The nozzle section 15 of the duct 1 is electrically connected by a conductor 19 to a source of high voltage direct current 20 which is suitably grounded, as indicated at 21 to form a grounded return circuit to the corona electrode 8. The high voltage power supply 20, which can be of the well known step-up alternating current transformer and rectifier type, may supply an attractor electrode voltage of the order of 50,000 volts D.C.

Downstream from the nozzle section 15, the conduit 1 consists of an insulating section 25, which serves to conduct the high velocity gas stream seeded with positive ions or charged particles to a collector electrode section (not shown) similar to that disclosed in our patented power generation device, U.S. Patent 3,225,225, previously noted.

The system disclosed in FIG. 1 operates as follows. A suitable transport gas under high pressure is delivered from a source (not shown) into the inlet end of the section 2 of the duct system generally indicated by the reference numeral 1 and flows through the insulating section 3 of the duct 1 into the inlet portion 16 of the expansion nozzle 15 and flows through the nozzle throat 17 where the gas velocity is sonic. When the nozzle 15 is

charged by the power supply 20 to a high negative electrostatic potential, the field created at the heated tip of the corona electrode results in the production and the acceleration of positive ions into the high velocity gas stream at or near the nozzle throat. The ions are swept downstream through the expanding section 18 of the nozzle to ultimately be collected on collector plates (not shown) in the manner as illustrated and described in our Patent No. 3,225,225, previously noted.

During operation, the corona electrode tip 8 is continuously heated by current through conductors 6, 11 and 12 from battery 10 or other direct current source. By thus being heated to a high temperature, the gas boundary layer in the vicinity of the electrode will be reduced in density permitting a copious flow of positive ions at high stream pressures and densities. The invention accordingly makes it possible to greatly increase the electrical power output capacity of equipment of the type as described in our prior Patent No. 3,225,225 by making it possible to have copious ion generation at greatly increased transport gas pressure and density.

FIG. 2 illustrates a structure similar to FIG. 1 except that the corona electrode is in the form of a ring. As seen in FIG. 2, the cylindrical insulating corona electrode holder indicated by the reference numeral 4 is provided with a streamlined nose portion 4a of smaller root diameter than that of the holder 4 leaving an offset or recess 30 formed with a groove 32 which is semicircular in cross section. The groove 32 is adapted to receive a ring-shaped electrode 35, which may be in the form of a complete circle except for a single gap. The ring electrode 35 is made of high resistance metal alloy and adapted to be heated to high temperature by direct current applied from an external source by conductors 6 similar to FIG. 1. If desired, the ring electrode 35 may be hollow and indirectly electrically heated by a heater coil (not shown) positioned within the electrode. The electrode 35 serves the same function as the corona electrode 8 of FIG. 1. The streamlined nose portion 4a of the corona electrode holder 4 serves to form with the attractor electrode 15 a diverging section 18 of the expansion nozzle. The ring electrode 35 is positioned at or near the throat section 17 of the nozzle. 15. The offset or recess 30 serves to provide a sheltered zone for the ring electrode 35 so that a high temperature gas blanket will surround the exterior of the ring electrode 35 and provide for easy escape of ions with a broader angle of distribution than from electrode 8 of FIG. 1 and also providing a more stable corona discharge.

We claim:

1. In an electro-fluid-dynamic power conversion apparatus of the character described, a conduit adapted to be connected to a source of high pressure gas or vapor, a

5 nozzle in said conduit, said nozzle having inlet, throat and diverging sections, said nozzle being adapted to expand the flow of gas therethrough to substantially sonic velocity or higher, said nozzle having at least the inner portions thereof made of an electrically conducting material, said nozzle being electrically insulated from the other portions of said conduit, a source of high electrical potential, the conducting portions of said nozzle being connected to said source of high electrical potential and serving as an attractor electrode, a corona electrode positioned within said conduit adjacent the throat section of said expansion nozzle, said corona electrode adapted to cooperate with the attractor electrode to cause a corona discharge therebetween and means for heating said corona electrode to a high temperature while the high pressure gas stream flows thereover.

10 2. The structure as claimed in claim 1, in which the corona generating electrode is a high resistance electrically conducting material substantially of conical shape with the tip portion positioned substantially at the throat section of the expansion nozzle, electrical conductors supported within and insulated from said duct and connected to said corona generating electrode and an external electric circuit connected to said conductors and including a power source and a connection from said external circuit to ground.

15 3. The structure as claimed in claim 1, in which the corona generating electrode is substantially ring-shaped and positioned substantially at the throat of the expansion nozzle which serves also as an attractor electrode, a substantially cylindrical insulating support positioned within said duct with its longitudinal axis concentric with said expansion nozzle, said cylindrical support having a streamlined nose section having a base diameter smaller than the diameter of the cylindrical support to form an offset portion, a semicylindrical groove in said offset portion housing said corona generating electrode and said electrode being sheltered from direct contact with the high pressure, the high velocity gas stream and conductors connecting said corona electrode to a source for heating the corona electrode to a high temperature.
